SHIRT

Alfreds Tenisons, Bellefontaine, Ohio

Application October 16, 1952, Serial No. 315,026

4 Claims. (Cl. 2—124)

1

The present invention relates to haberdashery and more particularly to shirts with cuffs.

A shirt usually becomes soiled at the cuffs due to the tendency of the cuff to pick up foreign material lodging on a surface on which the arm is momentarily resting. When this occurs in the case of an ordinary shirt, the latter has to be laundered even though the shirt, except the cuffs, may still be fresh and clean.

Again, it often happens after the shirt has been laundered, that the sleeve has shrunk, so that here again, in the case of an ordinary shirt, the latter can not further be used without discomfort and perhaps embarrassment to the wearer.

In my co-pending application Serial No. 315,025, filed October 16, 1952, there is disclosed a cuff construction which, incidental to providing a fresh, unsoiled edge at the folding line of a "French" cuff, also produces elongation of the cuff and therefore of the sleeve as a whole. However, in the present invention, this elongation is provided independently of the cuff and takes place at a position remote from the forward folding edge of the cuff.

The primary object of this invention is to provide a cuffed shirt in which provision is made for the wearer to present, in effect, a clean cuff in place of a soiled cuff.

Another object is to provide a shirt having replaceable cuffs so that when one cuff has become soiled, the soiled cuff can be replaced by a clean cuff and thereby eliminate the necessity for immediate laundering of the shirt.

Another object is to provide a cuffed shirt with a reversible cuff in which a soiled cuff surface can be replaced by a fresh clean surface by reversing the cuff surface.

Still another object is to provide a cuffed shirt in which the cuff is constituted of two reversible cuff portions and is secured to a sleeve by an extension element which is held in a non-extensible position by temporary holding means.

A further object is to provide a cuff adapted to be detachably secured to the shirt and in which the cuff can be removed from the shirt and replaced by a second cuff in order to present a clean surface without immediate laundering.

Another object is to provide a cuff shirt in which the cuff includes an extensible member for lengthening the cuff when desired.

The final object is to provide a cuff adapted to be detachably secured to a shirt and in which the cuff not only can be lengthened in a position remote from the folding edge but also can be

reversed at the folding edge to present a clean surface when desired.

Other objects and features will be apparent as the specification is perused in connection with the accompanying drawings in which:

Figure 1 represents a perspective view of the improved cuff attached as by sewing to the wrist band of a shirt;

Figure 2 shows, also in perspective, the finished cuff as applied to a sleeve, the ends of the cuff being secured together by cuff links;

Figure 3 is a fragmentary view of the cuff showing the extensive portion of the cuff when the latter is detachably applied to the shirt;

Figure 4 is a view similar to Figure 3, but showing the extensible cuff permanently secured as by sewing to the sleeve;

Figure 5 represents in perspective, the finished cuff of the type which is detachably secured to the sleeve, the lower corners of the cuff being pulled upwardly to expose the fastening means;

Figure 6 represents a plan view of the cuff attached to the sleeve either by permanently sewing or by the use of snaps and in which the cuff is temporarily held by removable stitches in a fore-shortened condition; and

Figure 7 is an end view of the cuff shown in Figure 6 and indicates the manner in which the outer cuff portion can be folded either upwardly or downwardly at the folding edge to provide a change in the external surface.

Referring to Figure 1, reference character 1 designates the sleeve of a shirt which is provided with a folded over and stitched wrist band 2 in order to provide reinforcement at this point.

The cuff, which is generally indicated at 3 is of the folded back type usually designated as a "French" cuff and the lateral edges of the cuff, indicated at 4 are usually temporarily joined together by a cuff link 5 (Figure 2) to give the required dress appearance. This cuff link passes through openings 6 at each end of the cuff as a whole, and approximately midway of the length of the cuff as measured in the sleeve direction.

The cuff may be formed of two portions 7, 8, the cuff portion 7 being shown on the outside of the cuff in Figure 1 although it will be understood that this cuff portion can be reversed and moved to the inside of the cuff, leaving the cuff portion 8 as the external surface element as will be explained hereinafter. The cuff portions 7, 8 are each preferably constituted of two thicknesses of sleeve material to give the proper stiffness.

As shown in Figure 6 the cuff portions are in-

tegrally joined at the folding edge 9 and these portions are substantially rectangular except for inwardly extending and curved cut-away portions 10 at each end of the folding line 9. The double thicknesses of material, which constitute the portion 7, 8 are sewed together as indicated at 11, the line of stitches constituting a wide border around each of the portions, except at the folding edge 9 in which the stitches are deliberately positioned close to the folding edge so as not to interfere with the neatness of the fold. The cuff portion 8 is made considerably wider than the portion 7 in order to provide a V-shaped extension 12 of which the lower layer of the extension may either be sewed to the wrist band 2 by stitches 13 as indicated in Figure 4, or detachably secured to the wrist band by a series of snaps 14 indicated in Figure 5.

In order to hold the extension 12 in its pleated or non-extensible position as shown in Figure 7, a series of stitches 15 (Figure 4), may be applied, usually three or four stitches in each group, and the stitch groups are positioned in four or five places along the length of the cuff as measured parallel to the folding edge. These stitches 15 may be cut by inserting a knife between the folds 16, 17 (Figs. 3 and 4), whereupon the extensible members 12 can be elongated by the double length of the fold 17, thus giving added length to the cuff member 8 in the direction of the sleeve length.

It will be apparent that the stitches 15 will hold the accordion extension 12 in a tight or non-extensible position indefinitely if desired, so that a fore-shortened sleeve length may be obtained in this manner. However, upon cutting the stitches 15 and removing the loose ends, the sleeve length is increased by twice the width of the fold 17 and this width can be made one-half inch or more as desired, so as to add at least an inch to the sleeve length.

The cuff portion 7 is adapted to be folded either over the cuff portion 8 as indicated by the dot-dash lines 7' in Figure 7 or may be folded under the cuff portion 8 as indicated at 7''. Thus, when the cuff portion 7 is superposed on the cuff portion 8 and the outer surface of the cuff becomes soiled, it is a simple matter for the wearer to remove the cuff link 5 and then fold the cuff portion 7 to a position under the cuff portion 8 in which case the outer or upper surface of the cuff portion 8 now becomes the exterior surface. This feature is of considerable benefit to persons who may not have the immediate facilities of laundering the shirt when only the cuffs become soiled, because in that case it is necessary merely to turn or reverse the cuff 7 from the top to the underneath side of the other cuff portion 8. The improved cuff, including the extension 12, can readily be cut and sewed together out of two thicknesses of shirt material because the extension 12 is in a flat condition when being made and is folded to form an accordion pleat or extension at the same time that the fastened means which may constitute the stitches 11 or the snaps 14 are being applied to the wrist band 2.

When the cuff 3 is secured to the wrist band in a detachable manner such as by the snaps 14 or a zipper or even buttons, the cuff as a whole can be removed from the wrist band and the cuff only be laundered, if the remainder of the shirt is still fresh and clean, so that considerable saving can be made in laundry expense by utilizing the cuffs of the character disclosed herein. How-

ever, it will be found more expedient when the cuff surface becomes soiled to reverse these cuff surfaces in the manner shown and described in connection with Figure 7, rather than remove the cuff as a whole from the wrist band.

From the foregoing it is evident that I have disclosed an improved cuff of the French foldable type in which the foldable elements can be reversed to present a clean laundered surface in place of a soiled surface and in addition, an extension is provided at the wrist band end of the cuff by which the cuff, and therefore the length of the sleeve can be greatly increased by the expedient of cutting or otherwise removing a few groups of stitches 15. This extension feature is equally adaptable to the improved cuffs which are either permanently sewed to the wrist band as shown in Figure 4 or are detachably secured to said band as shown in Figure 3.

It will be understood that various modifications and arrangements in structure could be made without departing from the spirit of my invention and, accordingly, I desire to comprehend such modifications and substitutions of equivalents as may be considered to come within the scope of the appended claims.

Having thus fully described my invention, what I claim as new and desire to secure by Letters Patent is:

1. A fold-over cuff for a shirt, said cuff comprising a first cuff portion, a second cuff portion integral with said first cuff portion, a cuff portion fold interconnecting said cuff portions, said cuff portions folded alongside each other along the cuff portion fold, a portion of said second cuff portion projecting beyond the edge of said first cuff portion when said cuff portions are in the folded position, the length of said projecting portion being less than the length of said first cuff portion, said projecting portion folded in a contracted position against said second cuff portion whereby said folded projecting portion may be unfolded to increase the length of the cuff, said contracted projecting portion being adapted to be detachably attached to a shirt sleeve.

2. A fold-over cuff for a shirt, said cuff comprising a first cuff portion, a second cuff portion integral with said first cuff portion, a cuff portion fold interconnecting said cuff portions, said cuff portions folded alongside each other along the cuff portion fold, a portion of said second cuff portion projecting beyond the edge of said first cuff portion when said cuff portions are in the folded position, the length of said projecting portion being less than the length of said first cuff portion, said projecting portion folded in alongside said second cuff portion on a line coinciding with the edge of said first cuff portion, said projecting portion folded again outwardly so that the edge of said projecting portion coincides with the edge of said first cuff portion, stitching means to retain said folded projecting portion in a contracted position whereby removal of said stitching means will permit the projecting portion to be unfolded thereby increasing the length of the cuff, said contracted projecting portion adapted to be detachably attached to a shirt sleeve.

3. In combination, a shirt sleeve terminating in a wristband, said wristband comprising an end portion of the sleeve being folded against the sleeve and attached thereto, a fold-over cuff for a shirt sleeve, said cuff comprising a first cuff portion, a second cuff portion integral with said first cuff portion, a cuff portion fold intercon-

necting said cuff portions, said cuff portions folded alongside each other along the cuff portion fold, a portion of said second cuff portion projecting beyond the edge of said first cuff portion when said cuff portions are in the folded position, said projecting portion folded in alongside said second cuff portion on a line coinciding with the edge of said first cuff portion, said projecting portion folded again outwardly so that the edge of said projecting portion coincides with the edge of 10 said first cuff portion, said folded projecting portion being less than the length of the first cuff portion, said folded projecting portion being detachably attached to said wristband.

4. A fold-over cuff for a shirt, said cuff comprising a first cuff portion, a second cuff portion integral with said first cuff portion, a cuff portion fold interconnecting said cuff portions, said cuff portions folded alongside each other along the cuff portion fold, a portion of said second cuff portion 15 projecting beyond the edge of said first cuff portion when said cuff portions are in the folded position, said projecting portion folded in along-

side the second cuff portion on a line coinciding with the edge of the first cuff portion, said projecting portion folded again outwardly so that the edge of said projecting portion coincides with the 5 edge of said first cuff portion, said folded projecting portion being less than one-half of the length of the first cuff portion, said folded projecting portion being adapted to be detachably secured to the end of a shirt sleeve.
